CLAIM

The ornamental design for a crisper box, as shown and described.

DESCRIPTION

FIG. 1 is a top perspective view of a crisper box, showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a top perspective view of the crisper box, when in the handle is in an open state.

The broken lines shown in the drawings are included for the purpose of illustrating portions of the crisper box that form no part of the claimed design.
